UNITED STATES PATENT OFFICE.

LEE T. ALTON, OF BROOKLYN, NEW YORK.

DESIGN FOR A TUBE FOR BURNERS.

SPECIFICATION forming part of Design No. 27,720, dated October 12, 1897.

Application filed August 21, 1897. Serial No. 649,085. Term of patent 7 years.

To all whom it may concern:

Be it known that I, LEE T. ALTON, a citizen of the United States, residing at Brooklyn, county of Kings, and State of New York 5 have invented and produced a new and original Design for Tubes for Incandescent or Bunsen Burners, of which the following is a specification, reference being had to the accompanying drawings, forming part of this specification, in which—

Figure 1 is a front elevation, and Fig. 2 a sectional elevation on the line $x x$, Fig. 1, of a tube embodying my invention.

The invention consists in a tube comprising 15 a series of superposed cylinder-sections connected by a series of cone frusta.

In the drawings, 1 2 3 4 5 indicate the superposed series of tube-sections, each one of larger diameter than the one below it, the 20 one of largest diameter being at the top, and

the one of smallest diameter at the bottom, and at 6 7 8 9 is indicated the cone frusta connecting the adjacent edges of the cylinder-sections, the cone frusta being inverted, the largest diameter being uppermost. All 25 of the parts are joined together and form an unbroken and continuous tube comprising the alternating cylinder-sections and cone frusta.

Having described my invention, I claim— 30

The design for a tube for incandescent or Bunsen burners, substantially as herein shown and described.

Signed at the city of Brooklyn, county of Kings, and State of New York, this 19th day 35 of August, 1897.

LEE T. ALTON.
